UNITED STATES PATENT OFFICE.

PHILIP H. CHASE, OF BALA, AND WILLIAM FOSTER, OF PHILADELPHIA, PENNSYLVANIA; SAID FOSTER ASSIGNOR TO SAID CHASE.

RACK.

Application filed January 28, 1926. Serial No. 84,484.

This invention relates to racks and with regard to certain more specific features to racks for insulators and like fixtures.

Among the several objects of the invention may be noted the provision of a rack comprising interchangeable units adapted to be fastened together to form various sized and shaped larger aggregate units; the provision of a rack of the type described which is adapted to be readily assembled in the field and be transported thereto with ease; the provision of a device of the type described which readily lends itself to manufacture in different unitary sizes and shapes; and the provision of such a device as described as is simple and economical of fabrication and of such ruggedness as to be adapted to long and hard usage. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings in which are illustrated various embodiments of the invention,

Fig. 1 is a side elevation showing one form of assembly of the general type of rack units described herein, and illustrates one modification of the general type;

Fig. 2 is a view similar to Fig. 1 showing another form of assembly;

Fig. 3 is a view similar to Fig. 1 showing a third form of assembly;

Fig. 4 is a plan view of Fig. 1;

Fig. 5 is a fragmentary side elevation showing a modified form of interlock between units;

Fig. 6 is an isometric view showing the form of unit of Fig. 5;

Fig. 7 is a fragmentary isometric view showing another form of interlock between units;

Fig. 8 is a fragmentary section taken on line 8-8 of Fig. 9;

Fig. 9 is a fragmentary side elevation showing a clamping ring for joining units;

Fig. 10 is a vertical section of the device shown in Fig. 1 but shows a modified form of leg therefor and a modified clamping ring;

Fig. 11 is a section taken on line 11-11 of Fig. 10;

Fig. 12 is a side elevation of another modified unit assembly;

Fig. 13 is a section taken on line 13-13 of Fig. 12;

Fig. 14 is a side elevation similar to Fig. 12 but shows another form of interlock;

Fig. 15 is a fragmentary section taken on line 15-15 of Fig. 14;

Fig. 16 is a plan view showing a form of fastening for using screws and the like;

Fig. 17 is a fragmentary side elevation of Fig. 16; and

Fig. 18 is a side elevation of an assembly showing another form of screw fastening.

Similar reference characters indicate corresponding parts throughout the several views of the drawings.

Referring now more particularly to Fig. 1, there is illustrated at numeral 1 a framework from which a group of insulators is to be suspended. In application, the framework 1 may be arranged as shown, or horizontally. The insulators 3 are adapted to have cables and the like fastened to them when said insulators are in any of various positions. This is accomplished by proper methods of wiring and shaping of the insulators or by direct gravity suspension if the framework 1 is horizontally arranged.

Heretofore the bracket or rack for holding a group of insulators has been formed in one unit. Hence, for every new combination of insulators (according to number and arrangement) a different sized and shaped rack has been required to be manufactured. This practice has led to waste in said manufacture and produced a clumsy product which was not readily transported or hoisted into fastening position. Furthermore, the exact combination of insulators to be required in a particular field installation cannot always be forecasted so that it is at present necessary to carry some racks of each of several descriptions to the point of installation so that all contingencies may be provided for.

In the present invention the rack assembly is formed in U-shaped units 5, each one of which comprises a more or less flat base portion 7 formed with a hole 9 preferably more or less centrally thereof. Each hole 9 provides means for fastening each respective unit 5 to the frame 1 by means either

of a bolt or lag screw 11. The choice between bolt or lag screw depends upon particular circumstances. Either is adapted to hold rather heavy loads.

5 Each unit 5 has formed angularly with respect to the portion 7, more or less flat legs 13. (See also Fig. 4.) Toward the base of the legs are formed aligned holes 15. These holes align with one another 10 when the portions 7 of several units 5 are aligned as shown in Fig. 1. Hence nut-and-bolt combinations 17 are adapted to hold two or more of the units together.

The outer ends of said legs 13 are also provided with aligned holes 19. Through these 15 holes 19 an aligning and supporting bolt 21 is passed for purposes of aligning the ends of the legs and supporting a group of insulators. The insulators are provided with the 20 proper hole for permitting their positioning on the bolt 21 and between the legs 13.

Each unit 5 is like its mate. These units are easily made, may be closely packed for transportation and can be readily assembled 25 at the support 1 to form a rack having a capacity for any desired number of insulators. Furthermore, if it is desired to increase the capacity of a rack after installation, it may readily be done without disturbing the previous wiring, merely by adding a unit 5 and introducing a longer bolt directly behind the bolt 21 as said bolt 21 is withdrawn from the holes 19 and insulators 3.

30 It is apparent from Fig. 2 that in order to increase the carrying capacity of a unit 5, it may be formed as the unit 23 of said Fig. 2 is formed. Each unit 23 comprises the same elements as a unit 5, that is, at and 35 near its base portions, but its legs 25 are lengthened to approximately double the length of the said legs 13 of the units 5. Hence by forming aligned holes 27 near the ends of said legs 25 another insulator 3 may 40 be added. Another shorter through bolt 29 holds this last named insulator.

If an inverse arrangement of insulators is desired from that shown in Fig. 2, it is only necessary to provide two long units 23 on 45 each side of a short unit 5 as illustrated in Fig. 3. Two long bolts 21 are then used for alignment and insulator mounting.

As indicated in Fig. 3 by dotted lines, the assembly there shown may be made to support two full rows of insulators, thus doubling the capacity of the Fig. 1 assembly. Preferably the outer central insulator is provided with spacer washers 31 one on each side thereof for aligning said insulator in 50 the absence of lengthened legs on the central unit 5. The combinations shown in Figs. 1 to 4 may be repeated to aggregate larger assemblies and the combinations may also be varied as to the manner of placing the units 55 5 and 23 and/or the insulators 3 (see dotted

lines, Fig. 3). It is therefore obvious that a flexible system of brackets or racks has been here devised. With a relatively small variety of parts a lineman or the like can device many kinds and sizes of brackets at the field 70 of installation.

Figs. 5 and 6 illustrate a somewhat more expeditiously operated locking means for use in aggregating units. As shown in Fig. 6 each unit 5 comprises said flat base portion 7 having said bolt hole 9 therethrough for purposes of fastening the unit to a brace or the like. Formed at an angle with said portion 7 are the said legs 13, at the outer ends of which are formed the said holes 19 80 for the through bolt 21. The unit is modified however in that the nut-and-bolt clamping combinations 17 for holding the units 6 together (shown in Figs. 1 to 4) are dispensed with. Instead, the opposite legs 13 85 are formed as follows:

One of legs 13 has a more or less rectangular portion punched therefrom to form an opening 33. On the opposite leg at a point somewhat nearer the portion 7 is formed a struck out but parallel tongue 35. The tongue 35 is slightly narrower than the opening 33. It is struck out a distance somewhat greater than the thickness of either of the legs 13. By placing a leg having a tongue 35, against one having the opening 33, the tongue 35 may be made to pass laterally through said opening. Then if the portions 7 of said juxtaposed units are aligned, the tongues 35 will slide down to hook over the portion of the legs 13 beneath the opening 33, whereby the units 5 are held together as long as the fastening bolts or lag screws 11 hold the respective units to the frame 1 (see Fig. 5). The result is a device 100 as rugged and effective as the one illustrated in Figs. 1 to 4 and one which may be modified as to assembly in the manner previously described for said first form. The present modified tongued connection eliminates the 105 nut-and-bolt combination 17. Hence there are fewer parts to assemble and to become liable to loss during transportation or assembly.

Fig. 7 illustrates another another form of struck-up tongue 37 which is T-shaped. The more or less oppositely formed opening 39 in the opposite leg of the unit 5 is also T-shaped but of greater dimensions than said tongue 37. Obviously in forming the T-headed tongue 37, the curvature given to the stem 41 thereof causes the cross portion 43 thereof to be positioned in projection somewhat over the stem of the slot left after striking up the tongue. Therefore if the opening 39 is formed oppositely of the opening formed by tongue 37, then one unit 5 will have to be moved along the other to make the cross-portion 43 of tongue 37 register with the cross portion of an opening 39. 130

The tongue is struck up such a distance that after passage sidewardly through the opening 39, it may be slipped rearwardly in the opening 39 until the said flat portions 7 of the units 5 (or 23) are aligned, whence the cross portion 43 is positioned across the stem of the T-opening 39. A positive interlock between units 5 and/or 23 is thus formed. Neither of the tongue forms 35 or 37 interfere with the placement of insulators 3 after assembly.

Figs. 12 and 13 show a form of sliding lock between units. Here one leg of the units 5 or 23 is left only with a hole 19 or holes 19 and 27 for receiving aligning and supporting bolts such as 21 or 29, the number of holes depending upon whether it is a short unit 5 or a long unit 23. The other leg of the unit is provided with a pair of sidewardly hooked ears adapted to slidably embrace the opposite plain leg of an adjacent unit. Units 5 or 23 may be slid on or off one another as desired to form various aggregate assemblies. They are fastened to the brace 1 in the manner hereinbefore described, that is by bolting through the holes 9. The legs on which the ears 45 are formed are also provided with the proper aligning holes 19 and/or 27 for receiving through bolts as described.

Figs. 14 and 15 show a type of interlock which requires lateral movement of the units 5 or 23 for assembly thereof. In this case one leg of each member has oppositely placed notches 47 formed near the base position thereof. In the other leg are formed up struck ears 49 adapted to cooperate snugly with the notches 47 when the units are laterally brought together with the base portions 7 aligned. The depth of each notch 47 is approximately twice the thickness of the material used for forming the legs 13. The upstruck ears 49 have a similar effective length so that when said ears 49 and notches 47 cooperate, a lateral flush arrangement is obtained (see Fig. 14). All other elements on the units 5 or 23 in this form are like those of the previous forms.

It may be noted that the Fig. 1 to 4 fastening form may be assembled by moving the units 4 or 23 in any of many ways. The forms of Figs. 5 to 7 require a compound lateral and longitudinal movement. The form of Figs. 12 and 13 requires only a longitudinal movement, while the form of Figs. 14 and 15 requires only a lateral movement. The particular class of service will govern the desirability of a particular form of interlock or fastening.

Figs. 8 and 9 show a fastener 51 which comprises a raised hollow frame or collar 53 adapted to snugly fit around two legs of adjacent units 5 or 23. It is slid down against the flat portions 7 of said units. It is provided with sidewardly extending off-

set legs or lugs 55 drilled for purposes of screwing or bolting to a frame 1. This fastener is adapted to be used where screws are used as fasteners and whereby a relatively long tool must be used for application thereof. The previous forms, after installation would not permit of the use of a long tool such as a screw driver for reaching the fastenings 11 passing through the holes 9 because the insulators and through bolts would interfere. In the present form this is not true. Here the holes 9 may be eliminated.

Figs. 10 and 11 show how the legs 13 and/or 25 of the units 5 and/or 23 may be modified to advantage. They are laterally and inwardly bowed as indicated at numeral 57. Approximately elliptically formed fastening rings or collars 59 are then slipped over adjacent legs of juxtaposed units. This form, after being fastened to the frame 1 by proper fasteners passing through the holes 9, provides pairs of extending legs 13 or 25 which themselves form hollow sectioned bracing members whose combined section modulus is higher than that of two adjacent flat members of like proportions. Hence strength is increased. Furthermore burred edges are prevented from scraping the insulation from cables and the like which may be drawn through the unit during installation (see dotted lines, Fig. 10). It is to be understood that if desired, the rings 59 may be provided with ears for screwing them to the frame 1, the construction being similar to the one shown in Figs. 8 and 9. They may then act additively with the fasteners of holes 9 or replace them. Likewise the ears on the frames 51 of the Figs. 8 and 9 form may be dispensed with and the fasteners 11 employed with holes 9.

Figs. 16 to 18 show means for adapting any of the previous forms to be fastened in such manner that the fastenings for removing the assembly as a whole may readily be reached without interference from the through bolts 21 or 29 and/or the insulators 3.

In Figs. 16 and 17 each Fig. 1 form of unit 5 is bolted to a lateral bridge member 61. The arched portion 63 of each member 61 is raised above the lower surface of its supporting legs 65 enough to permit placement of a bolt head 67 under the bridge. A hole 69 formed through the bridge is adapted to align with the said hole 9 of the units 5 and/or 23 and receive a nut-and-bolt combination 71 for fastening the said unit to its bridge. Holes 73 in the legs 65 permit passage of lag or other fastening screws 75 and the like. The fasteners 75 may readily be reached by a screw driver, socket wrench or other long handled more or less vertically operable instrument. The arched portion 63 of the bridge is of such length that an end wrench may be applied to the head of

the fastener 71. Any of the previously described forms of interlocked units 5 having fastening holes 9 may be fastened by means of these bridges, or the one about to be described.

Fig. 18 shows the use of one long bridge 77 which has an arch 79 long enough to laterally receive all of a group of units 5 and/or 23. As in the previous form, nut-and-bolt combinations 67 hold the units to the bridge 79, which bridge has the requisite number of holes formed therein. Legs 81 are adapted to be screwed or held down by fasteners 83 which are easily reached without interference from the units themselves.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that matter contained in the above description or shown in the accompanying drawings shall be interpreted as illustrative and not in a limiting sense.

We claim:

1. A rack for insulators and the like comprising interchangeable units adapted to be fastened together in various juxtapositioned combinations and aggregations while in the process of installation, said units comprising portions adapted to be fastened to a common frame and laterally formed legs the adjacent legs of juxtapositioned units being held together, and a bolt passing thru the legs of the units and upon which the insulators are mounted.

2. A rack for insulators and the like comprising interchangeable units adapted to be fastened together and to a common frame in various combinations and aggregations, said units comprising portions adapted to be fastened to a frame, laterally formed legs adapted to lie adjacent to the legs of adjacent units, tongue-and-slot combinations for

holding adjacent legs of the units together and a through bolt passing through holes formed in the legs whereby the units are aligned and whereby insulators may be held between them.

3. A rack for insulators and the like comprising interchangeable units adapted to be fastened together and to a common frame in various combinations and aggregations, said units comprising portions adapted to be fastened to a frame, laterally formed legs adapted to lie adjacent to the legs of adjacent units, means for holding adjacent legs of the units together and a through bolt passing through holes formed in the legs whereby the units are aligned and whereby insulators may be held between them.

4. A rack for insulators and the like comprising interchangeable units adapted to be fastened together and to a common frame in various combinations and aggregations, said units comprising portions adapted to be fastened to a frame, laterally formed legs of various lengths adapted to lie adjacent to the legs of adjacent units, means for holding adjacent legs of the units together and a through bolt passing through holes formed in the legs whereby the units are aligned and whereby insulators may be held between them.

5. A rack for insulators and the like comprising a plurality of U-shaped units, means for fastening said units to a common frame, at least one opening in one leg of each unit and at least one corresponding tongue on the other leg thereof, said openings and tongues being adapted to engage corresponding tongues and openings respectively on other juxtapositioned units, to hold the units to one another, aligned openings in the units and bolts adapted to pass through said last-named openings to align the units and support insulators thereon.

In testimony whereof, we have signed our names to this specification this 27th day of January, 1926, and this 27th day of January, 1926, respectively.

PHILIP H. CHASE.
WILLIAM FOSTER.
